[57] ABSTRACT

A device for producing tubular wrappings for paper bags with a mandrel wheel rotating stepwise in a horizontal plane and having horizontally outwardly extending pairs of spaced parallel folding mandrels. The blanks of bag material are fed horizontally toward a position below the folding mandrels and are brought into contact pressure with a bottom face of the folding mandrels by upwardly moving folding boxes, whereupon a folding fork associated with each folding box moves upwardly to place and wrap the blanks against the sides and around the folding mandrels with the assistance of compressed air.

DEVICE FOR PRODUCING BAGS BY MEANS OF A MANDREL WHEEL

The invention relates to a device for the production of bags by means of a stepwise rotating mandrel wheel cooperating with folding members, whereby said mandrel wheel has arranged thereon groups comprising each two parallel folding mandrels, and in which bag material blanks are placed at a treatment station on the two parallel folding mandrels to be formed by the latter into hose-like jackets, covers, or wrappings.

Devices of this type are already known. They have the advantage, that a doubling of the production may be attained, in that at each operative cycle, simultaneously two wrappings may be produced. These devices could, however, up to now be utilized solely for the production of bags with relatively small cross-sectional surface, as the space requirement for two folding boxes at the same working station was sufficient solely if the dimensions of the folding boxes did not exceed a certain limit. The size of the folding boxes is determined by the dimensions of the bag material blanks, which on their part depend on the size of the bags to be produced.

It has also been recommended to improve the space conditions for the arrangement of larger folding boxes by arranging the folding boxes with their feeding devices for the adjacent parallel folding mandrels at different stations of the mandrel wheel. This arrangement has, however, the disadvantage, that without substantial increase in the diameter and the number of the folding mandrels of the mandrel wheel solely single-walled bags may be produced. The number of the treatment stations required for the production of double-walled bags does not permit of being arranged in the utilization of mandrel wheels of ordinary size.

It is the object of the invention to overcome this disadvantage and to furnish a device with which at a treatment station two folding boxes of beyond average size may be arranged, which are not hindered by their working strokes.

The invention is characterized by two folding boxes pressing the blanks on the mandrels moved consecutively out of the feeding position into the contact pressure position on the mandrel and back, whereby the movement takes place along an inclined or arcuate path.

In this manner, the two folding boxes may be arranged in their feeding position, in which one blank at a time is fed to them, adjacent one another, while each folding box may engage in its contact pressure position partially in the space which is required by the other folding box. The production loss through the treatment step at this station, stacked as to time, is substantially less than upon utilization of a mandrel wheel with solely one folding mandrel per treatment station.

The drawing illustrates by way of example an embodiment of the device of the invention.

In the drawings:

FIG. 1 is a plan view of a portion of a mandrel wheel, with each two parallel folding mandrels and at one treatment station with two folding boxes;

FIG. 2 is a side elevation view of the treatment station shown in FIG. 1; and

FIGS. 3a, 3b and 3c illustrate diagrammatically each a different working position of the two folding boxes.

The mandrel wheel 1 of which only a portion is shown in FIG. 1 rotates with each two parallel outwardly extending folding mandrels 2a, 2b stepwise or intermittent in direction of the arrow, in such manner that the folding mandrels 2a, 2b stop at each one of the individual operating stations, so that the required treatment operations may be undertaken. In the Figures is shown the first of these treatment stations, in which a manner known per se there is supplied to the two folding boxes 3a, 3b, each a flat blank of the packaging material, for example, one made of paper, which is then placed about the folding mandrels and formed into a bag-like wrapping.

The two folding boxes 3a, 3b are pivotally connected each by two parallel guide levers 4, 5 with bearing supports 6. The

guide levers 4 are rigidly connected with arms 7 to which are pivotally attached actuating rods 8 which for example are lengthwise driven up and down by not shown cams, and may perform a lifting movement according to the double arrow 9.

During this lifting movement, the folding boxes 3a, 3b are moved from the feeding position shown at the left in FIG. 2 into the contact pressure position shown at the right-hand side of FIG. 2 whereby the movement takes place along an arcuate path shown by a dotted line 10.

With each one of the folding boxes 3a, 3b is furthermore combined a folding plate 11a, 11b. These plates perform approximately simultaneously with the folding boxes a vertical lifting movement for the pressing of the blank against the under side of the folding mandrel 2a, 2b. The plates 11a, 11b

15 are arranged on the upper ends of vertical rods 12a, 12b, which are guided coaxially in vertical posts 13a, 13b which on their part may perform a lifting movement independently of the rods 12a, 12b. The posts 13a, 13b carry on their upper ends folding forks 14a, 14b which serve for placing the blanks 20 against the side walls of the folding mandrels. The folding forks 14a, 14b are moved through recesses 17 in the folding boxes 3a, 3b.

Furthermore, compressed air conduits 15 are provided which terminate in nozzles 16. The jets of air issuing from

25 these nozzles serve for the alignment of the blanks in front of the folding forks 14a, 14b, so that the latter during their operating stroke place the blanks firmly against the side walls of the mandrels 2a, 2b.

The modus operandi of the device is as follows: As shown in FIG. 3a, there is conveyed in the illustrated feeding position to each folding box in a manner known per se a blank of the packaging material shown in dotted-dash lines. Now first the folding boxes 3a are lifted or transferred to the contact pressure position shown in FIG. 3b. Practically simultaneously the

35 folder plate 11a and the folding fork 14a are moved upwardly. The folder plate 11a presses the blank against the bottom surface of the folding mandrel 2a, while the folding fork 14a moves further upwardly so that the blank is placed against the side surfaces of the folding mandrel 2a. As soon as, however, 40 the folder plate 11a engages the folding mandrel 2a, the folding box 3a moves back again into its starting position. Now the left-hand folding box 3b is lifted and the operation described is repeated on the folding mandrel 2b.

The folding boxes, instead of being guided by double levers

45 5, could also be guided in another manner, for example by means of inclined slide-ways. In such a case, the folding boxes 3a, 3b would then not be moved along an arcuate path, but along a rectilinearly inclined path.

What I claim is:

50 1. In a bag making apparatus including an intermittently rotating wheel having angularly spaced groups of two spaced parallel folding mandrels said groups of spaced mandrels, upon rotation of said wheel, being movable to an operating station having folding means for supporting and transferring blanks of bag material into contact pressure with said folding mandrels to form a tube-like wrapping, the improvement wherein said folding members comprise two laterally spaced folding boxes for supporting and transferring two blanks of bag material into contact pressure with respective ones of said 55 mandrels, means for sequentially moving said folding boxes between a feed position in which the bag material is fed thereon and a fold position in which the blanks are in contact pressure with an associated mandrel to fold said blanks, and means mounting said folding members so that the movement of each of said folding members follows an arcuate path between said feed position and said pressure contact position, said means mounting said folding members comprising a bearing support, a pair of guide levers each pivotally connected at one end to said bearing support and pivotally connected at the other end to said folding boxes, and wherein said means for moving said folding boxes in said arcuate path is connected to said guide levers.
